UNITED STATES PATENT OFFICE.

HENRY J. MARX, OF HOLYOKE, MASSACHUSETTS, ASSIGNOR TO THE AMERICAN THREAD COMPANY, OF JERSEY CITY, NEW JERSEY, A CORPORATION OF NEW JERSEY.

DRUM-WINDER.

1,251,075.

Specification of Letters Patent. Patented Dec. 25, 1917.

Application filed April 4, 1917. Serial No. 159,600.

To all whom it may concern:

Be it known that I, HENRY J. MARX, a citizen of the United States, residing at Holyoke, county of Hampden, State of Massachusetts, have invented certain new and useful Improvements in Drum-Winders, of which the following is a full, clear, and exact description.

My invention relates to drum winders and has for its object to provide stop motions in such drum winders with a brake which in the operation of the stop motion will act to check the rotary movement of the bobbin and then release it so that it will turn easily and permit the thread to be pulled off as desired for the purpose of tying together the broken ends. It is an improvement on the device shown in application of H. J. Marx, Serial No. 72,003, filed January 14, 1916 (Patent No. 1,222,962), in which the brake when once applied stays in holding position so as to interfere with the unwinding of any thread.

The following is a description of my invention, reference being had to the accompanying drawings, in which:

Figure 1 is a front view of an embodiment of my invention.

Fig. 2 is a side elevation of the same; Fig. 3 is a front view of a portion of the brake member and coöperating part at one stage in the operation, and

Fig. 4 is a similar view with the parts as in another stage of their operation.

In Figs. 1, 3 and 4 the face plate is omitted to show the interior mechanism.

Referring more particularly to the drawings, 1 is a drum of a drum winder, 2 is a yoke holding a bobbin 3. 4 is a frame pivoted to a support 5 at 6 and pivoted to the yoke 2 at 7. 8 is a trip box movably mounted on the forward end of the frame 4 having trip-pins 9 which when released are engaged by the revolving striker 10 (Fig. 2) so as to throw the box with its projection 11 counter-clockwise (Fig. 2) and release a lever 12 pivoted to the frame 5 at 13 and connected to the yoke 2 by a slot surrounding the end of the pivot 7. When the lever 12 is released the yoke 2 falls down with the bobbin 3, which is then held away from the drum 1 by the separating shoe 14, all as described in said application. In order to stop the rotation of the bobbin a braking member is provided

consisting of a body portion 15 and brake shoes 16. This member has holes fitting over guiding-pins 17 carried by the yoke 2. The holes in the brake member contain springs 18 to counterbalance its weight and hold it out of rigid engagement with the yoke 2. The frame member is provided with a downwardly extending projection 19 which, as the yoke 2 falls upon the release of the lever 12, engages a stationary anvil 20 so as to prevent the brake member from moving downwardly with the yoke and make it engage the descending bobbin. The construction and action thus far described, with the exception of the counterbalancing springs, is the old construction and operation of said application.

In order to release the spool after the brake which stops it has been applied, I have in my present invention provided means for bringing about a disengagement of the braking member and bobbin after an interval of engagement. In the embodiment shown this consists in making the depending projection 19 movable relatively to the body of the brake member, forming in said body guiding surfaces 21, 21', the latter being, at its upper part, shallower than the former so as to form a vertical slot for a pawl 22 about to be described, and of full width at its lower end 21'. To the upper end of the movable member 19 I pivot a pawl 22, which normally tends to be moved by gravity to the position shown in Fig. 1. In that position it lies beneath a spring-controlled abutment 23 pivoted at 24 and held in depressed position by a spring 25 against a stop 26. Since the movement of the member 19 is blocked by the anvil 20 the pawl 22 is brought into engagement with the spring-controlled abutment 23, as shown in Fig. 3, so as to check its downward movement and consequently check the downward movement of the body portion of the brake member, bringing the bobbin into braking engagement with the brake shoes 16 so as to stop the bobbin. The bobbin and brake shoes continue to move down by gravity whereupon the pawl 22 moves the spring-controlled abutment 23, relatively to the body portion 15, as shown in dotted lines in Fig. 3, until the member 23 escapes by the pawl 22 whereupon the pawl 22 stays in the relative position shown in dots in Fig. 4, while the spring controlled abutment 23 snaps back to its normal position. The brake shoes

then fall away from the bobbin so that it is released by them. The separating shoe 14 does not have any substantial braking effect, the bobbin being held only lightly 5 against it by the action of the weight 27. When the yoke and spool are again lifted and latched so that the bobbin is again in engagement with the driving drum, the pawl 22 drags by the spring abutment 23, as 10 shown in Fig. 4, until the parts assume the relations shown in Fig. 1, ready to act upon the breaking of another thread. Holes 28 are for screws to secure a face plate which 15 acts as a cover.

15 As will be evident to those skilled in the art, my invention permits of various modifications without departing from the spirit thereof or the scope of the appended claims.

What I claim is:

20 1. In a drum winder a brake for a bobbin being wound, means for withdrawing said bobbin from the drum and applying said brake when a thread becomes broken, and means for subsequently releasing said brake 25 automatically after the rotation of the bobbin has been checked.

2. In a drum winder, the combination of 30 a yoke for holding a spool, means for withdrawing said spool from the drum when a thread breaks, a brake, means for applying said brake during the first part of the movement of said withdrawal, and means for automatically releasing said brake during a 35 later part of said movement of withdrawal.

3. In a drum winder, the combination of

a yoke for holding a spool, means for moving said yoke so as to withdraw said spool from the drum when a thread breaks, a brake carried by said yoke in the direction of which said spool moves as it is withdrawn, 40 means for temporarily preventing said brake from moving along with said spool, and means for later releasing said brake from said preventing means.

4. In a brake for a drum winder, a body 45 portion carrying a braking surface adapted to engage a bobbin, a plunger projecting therefrom and longitudinally movable relatively thereto, means for blocking the movement of said plunger as said body portion 50 and bobbin perform movements in the direction in which the projecting end of said plunger points, and means for temporarily supporting said plunger and body portion so as to check the movement of said body 55 portion during the first part of its movement in said direction.

5. In a brake for a drum winder the combination of a body portion having a braking surface adapted to engage a bobbin, a 60 plunger movable longitudinally relatively thereto, a spring-restrained abutment carried by said body portion, and a pawl pivoted to said plunger and adapted to make temporary holding engagement with said 65 spring-controlled abutment when said plunger is moving in one direction relatively thereto.

HENRY J. MARX.
